GAME APPARATUS

Carl J. Siegrist, Stockton, Kans.

Application August 6, 1937, Serial No. 157,788

3 Claims. (Cl. 273—51)

This invention appertains to new and useful improvements in amusement apparatus, and more particularly to an apparatus of the surface projectile type.

5 The principal object of the present invention is to provide a game apparatus in the nature of a bowling alley of the table type along which balls may be rolled or projected with a minimum amount of sound.

10 Another important object of the invention is to provide a bumper background for absorbing shock and minimizing sound as the pins are struck by the played balls.

15 Other important objects and advantages of the invention will become apparent to the reader of the following specification.

In the drawings:

Figures 1a and 1b represent a longitudinal sectional view through the apparatus.

20 Figure 2 is a fragmentary top plan view of the apparatus.

Figure 3 is an end elevational view of the structure.

Figure 4 is a cross-sectional view.

25 Figure 5 is a fragmentary sectional view.

Figure 6 is a sectional view taken substantially on line 6—6 of Figure 2.

30 Figure 7 is a detail view partly in section showing how a rail is supported at an end of a partition section and showing the pin for connecting two rail sections together.

35 Referring to the drawings, wherein like numerals designate like parts, it can be seen that the alley construction is made up of sections A, B and C. If desired, more sections can be employed or shorter sections than those represented.

The sections are provided with cross-members 5 and 6 which interlap as shown in Figure 1a and 1b and each of these sections is provided with a pair of elongated beams 7—7 for each alley, which alleys are generally referred to by the numerals 8—9. The adjacent beams 7—7 of the alleys 8—9 bear against the opposite sides of the partition wall 10 and upon this partition wall at desirable spaced intervals are the blocks 11 supporting the ball return rails 13. Of course these rails 13 are formed in sections so that the alley sections A, B and C can be separated and one rail section is connected to an abutting end of another rail section by a pin 12 which fits in the two abutting ends as shown in Figure 7. As can be seen in Figure 1a, the back end of the partition 10 is stepped upwardly as at 14 and the rear ends of the ball return rails 13 are bent

backwardly as at 15 to form a stop. Furthermore, the forward end of this trackway is also bent backwardly as at 16 to serve as a stop for the returned balls.

The bed of the alleys consists of three plies 16, 17 and 18 of tempered pressed wood fiber or other suitable substance having suitable spacer strips 20 interposed between the same at desirable intervals. A suitable resilient filler 22 is provided between the plies and the alley beds constructed 10 in this manner define a structure which will materially absorb sound and greatly reduce the rumbling sound of rolling balls.

At the stepped ends of the side walls 23—23 and on opposite sides of the stepped portion 14 15 of the partition 10 are cushioning areas 24. A pair of bumper gates 25—25 are mounted at the rear end of the alley. At this end of the alley the partition 10 has the upstanding post 26 located thereat and this post extends through the 20 ears 27 of the gate carrying bars 28—29, the gate 25 being provided with loops 30 disposed over the said bars 28—29.

On the rear end of each of the side walls 23—23 a safety latch and shock absorbing unit such as 25 is generally referred to by numeral 31 is provided. This unit consists of the wall attaching leg 32 which extends vertically and has the portion 33 disposed laterally for disposition over the upper edge of the wall. Rising from this portion 30 32 is the portion 34 having an opening therein for receiving the plunger 35. A laterally extending arm 36 is provided on this portion 34, and this is provided with a barrel 37 at one end 35 engaged around the hinge pin 38.

Numerical 39 denotes a plate having the barrel 40 disposed around the hinge plate 38 and this barrel 40 is provided with the depending lug 41 having the slot 42 therein for slidably receiving the plunger 35.

A fixed collar 43 is provided on the plunger 35 and a coiled compressible spring 44 convoluted on the plunger 35 is interposed between the collar 43 and the lug 41 for normally tending to urge the plunger 35 into tensional engagement with the corresponding end of one of the bars 28—29. The plate 39 has its rear end curving downwardly as at 45 to engage with the bar 28. This downwardly curved portion 45 merges with the handle 46. Obviously, the handle can be lifted upwardly to release the corresponding bars 28—29 and as the handle 46 is lifted, the lug 41 will move the plunger 35 so as to dislodge the bar 28.

Furthermore, the spring 44 serves as a shock 55

absorbing adjunct for the corresponding gates 28-29.

Suitable brace means 41 can be provided between the post 26 and the gate bars 28-29.

- 5 Gullies 48 can be formed along each side of each of the alleys 2-9 and these can slant downwardly at their rear ends as at 49. Each gully is formed of an outer runner 48' which abuts a side wall of an alley and an inner runner 48'' which abuts the upper ply 17 of the bottom formation of the alley and said runner 48'' has a reduced part fitting in the space between the upper ply 17 and the intermediate ply 18 as shown in Figure 4. As also shown in Figure 4 10 these runners rest on the longitudinally extending beams 7.
- 10
- 15

An upwardly inclined short back wall 50 is provided at the pit 51.

While the foregoing specification sets forth the invention in specific terms, it is to be understood that numerous changes in the shape, size and materials may be resorted to without departing from the spirit and scope of the invention as claimed hereinafter.

20 25 Having thus described the invention, what is claimed as new is:

1. A game apparatus comprising a frame including a pair of spaced longitudinally extending beams, a floor structure extending across the upper portion of the space between the beams, upright members connected with the outer edges 30 of the beams and forming side walls and a pair of spaced gutter forming runners on each beam, one runner abutting a side edge portion of the floor structure, said floor structure including a plurality of longitudinally extending plies of sheet material vertically spaced and filling material placed between the plies.

of spaced gutter forming runners on each beam, one runner abutting a side edge portion of the floor structure.

2. A game apparatus comprising a frame including a pair of spaced longitudinally extending beams, a floor structure extending across the upper portion of the space between the beams, upright members connected with the outer edges 5 of the beams and forming side walls and a pair of spaced gutter forming runners on each beam, 10 one runner abutting a side edge portion of the floor structure, said floor structure including a plurality of longitudinally extending plies of sheet material vertically spaced and filling material placed between the plies.

3. A game apparatus comprising a frame including a pair of spaced longitudinally extending beams, a floor structure extending across the upper portion of the space between the beams, upright members connected with the outer edges 20 of the beams and forming side walls and a pair of spaced gutter forming runners on each beam, one runner abutting a side edge portion of the floor structure, said floor structure including a plurality of longitudinally extending plies of 25 sheet material vertically spaced and filling material placed between the plies, the upper ply being located above the upper plane of the upper edges of the beams and with its top flush with the top of the inner runners.

CARL J. SIEGRIST.
